BOX CONSTRUCTION

Leonard Sofo, Chicago, Ill., assignor to Plasticrest Products Inc., Chicago, Ill., a corporation of Illinois

Application August 9, 1948, Serial No. 43,171

3 Claims. (Cl. 220—38)

1

This invention relates to a novel box construction and more particularly to a display box in which the cover may be slid down the back of the box and thereby hidden from sight.

Although the novel construction of the present invention may be used for boxes, cases, crates or the like of all sizes, it is particularly applicable to boxes or cases used to display jewelry including rings, watches, necklaces, bracelets, ear rings, brooches, belt buckles, tie clasps, cuff links, etc. As it is customary for jewelers to display their merchandise on rows of shelves in windows and show cases, a major objection to the presently used boxes is that the covers of the boxes on one row of shelves block the display of jewelry on the adjacent back row of shelves. To overcome this objection, it has been necessary for jewelers to use less rows of shelves with further distance between them or to stagger the boxes, both of which cut down on the amount of jewelry which may be displayed in a given space. The novel box construction of the present invention eliminates the objection heretofore set forth without reducing the available display space.

The novel box of the present invention is constructed of three pieces comprising a body, a skirt or apron and a cover. The back part of the body is slotted and is provided with runners or railings on the inside of the back parallel to the slot. The cover is provided with a pin or wire which rides along the runners and thereby permits sliding the cover down the back of the body and out of sight. As hereinbefore set forth, this arrangement removes the cover from sight and permits the display of a greater quantity of merchandise in a given space. The skirt or apron serves both as an inside cover to prevent the outside cover from becoming disengaged and also as a skirt or shield to improve the appearance of the box. It is within the scope of the invention, when desired, to construct the skirt as a flat piece to serve solely to hold the outside cover and padding in place.

As a particular feature of the present invention, the pin in riding along the runners is under tension and thereby serves to hold the cover in any desired position at the back of the box. The pin is also under extra tension when the box is being closed and thereby will snap shut, and also is under tension in the closed position which serves to keep the cover tight against the body of the box and thereby prevents the jewelry from falling out of the box when it is being withdrawn from the window or show case or when the box is otherwise being moved from one place to another.

2

When opening the cover and thus overcoming the extra tension, the cover will snap open and this further facilitates use of the display box.

As another particular feature of the present invention, construction of the display box in three pieces offers the important advantage of facilitating installation of the padding into which the ring is inserted or on which other jewelry rests. The shield or apron hides the raw edges of the padding and thereby eliminates the necessity of resorting to complicated and expensive means to avoid the protruding of the raw edges as required in the display boxes heretofore used. Further, the padding is readily reinforced by cardboard, plastic or the like and need not be glued or cemented into the box, as it will be securely held in place by the cover portion of the skirt. As will be hereinafter described in detail, protuberances are provided on the inside of the body to coincide with the particular shape of the reinforcement to thereby hold the padding firmly in position.

The novelty and utility of the present invention will be explained further in describing the accompanying drawings which illustrate one specific embodiment of the invention.

Figure 1 is a front view of the novel box construction. In this view, the cover is illustrated in a lowered position by the full lines and in a raised position by the dotted lines. Figure 2 is a section taken along lines 2—2 of Figure 1. Figure 3 is a back view with the cover in a raised position. Figures 4, 5 and 6 illustrate the cover, body and shield respectively.

As hereinbefore set forth the drawings illustrate one specific embodiment of the invention which comprises a Marquis style box for use in displaying rings. It is understood that the novel construction of the present invention may be used in boxes of other shapes, including square, rectangular, triangular, round, oval, etc., and combinations thereof. The box may be made of any suitable material including plastic, wood, metal, etc., or combinations thereof.

Referring to Figure 1 of the drawings, numeral 45 1 represents the cover which is illustrated in a raised position by the dotted lines and in a lowered position by the full lines. Figure 4 of the drawings further illustrate the cover. It will be noted that the cover is beveled inwardly as illustrated at 2 and thus provides ample clearance for the ring or other jewelry in the box when the cover is closed. Usually cloth, felt or other padding is inserted inside the cover to protect the jewelry and also to improve the appearance of 50 the box. In the case here illustrated, pin 3 is 55

held in place by screw 4. It is understood that pin 3 may be round, flat, square or any other suitable design, including a flat piece with curved ends. Upraised member 5 contains a groove into which pin 3 is inserted and is held in place by screw 4. The clearance between the pin and the inside of the cover is designed so that the ends of the pin will be bent in riding the rails and the pin thereby will be under tension. Thus, this clearance will be less than the combined thickness of the body portion and railing. It is understood that any other suitable method of holding pin 3 to the cover may be employed, such as providing a hole in raised member 5 through which pin 3 may be inserted.

Referring again to Figure 1, numeral 6 represents the skirt or apron which also is illustrated in Figure 6. It will be noted that the skirt comprises an outwardly beveled bottom portion 7 and a flat top 8. The flat top is positioned at an angle to coincide with the angle of the body of the box in order to provide a close fit therewith, thereby serving as a rim or inside cover for the box. The flat top 8 is provided with slot 9 which is sized to receive raised member 5 of the cover.

In the front view of Figure 1, the body of the box is not shown but is illustrated in Figure 5 and also in Figures 2 and 3. Referring to Figure 5, it will be noted that body 10 comprises a boat shaped member having front 11, angular sides 12 and back 13. Back 13 is provided with slot 14 which coincides with slot 9 in skirt 6. Thus slot 14 is slightly larger in width than raised member 5 on cover 1. On the inside of back 13, runners or railings 15 are provided. These railings extend parallel to slot 14 and, because the railings are raised members, pin 3 is under tension and therefore will hold the cover in place in any position at the back of the box. The upper portion of back 13 is curved inwardly, as illustrated at 16, to provide a turning point for closing cover 1. In assembling the box, raised member 5 is inserted in slot 14 and pin 3 rides on railings 15. After the padding is inserted in the body, skirt 6 is glued, cemented or otherwise attached to body 10 and thereby serves to hold the padding in place and to prevent the cover from separating from the body, as well as to provide the balance of the turning point for closing the cover. The inside top portion of the skirt contains raised members, similar to but shorter than railings 15, on both sides of slot 9 so that pin 3 is also under tension when the cover is in a closed position to thereby hold the cover tight against the body.

Slot 14 is provided with indented portion 17 which may be of any desired shape and is provided to remove or insert the cover after the box has been assembled. This is accomplished by twisting the cover 90° at a point adjacent indented portion 17 which provides clearance for turning raised member 5 and thereby to swing the cover away from the body.

The reinforcement for the padding rests against raised portions 18 which extend further than railings 15 and thereby provide ample clearance for the pin to ride railings 15. The reinforcement also serves to improve the appearance of the rear view of the box by blocking vision into the inside of the box through slot 14. The remaining raised portions indicated at 19 are provided as guides to hold the padding in position and their exact location in the body will

depend upon the shape of the particular padding reinforcement being used.

Referring again to Figure 1 of the drawings, numeral 20 represents padding inserted in body 10. When the box is used to display a ring, a groove 21 will be provided in the center of the padding. When used to display other jewelry the padding usually will be provided with an opening of the desired shape to correspond with the particular jewelry to be displayed.

Figure 2 is a section taken along lines 2-2 of Figure 1. Cover 1 is in a lowered position. Numeral 22 represents a cloth padding inserted in the cover and held in position by cardboard reinforcing 23. Pin 3 is held in place in raised member 5 by means of screw 4. When raising or lowering the cover, pin 3 rides along railing 15 provided in body 10. The inside top of body 10 is curved inwardly at 16 so that the cover may be closed by raising it and pivoting pin 3 about the turning point. Skirt 6 is provided with raised members 26 at both sides of slot 9 which, as hereinbefore set forth, serves to keep pin 3 under tension when the cover is closed. It will be noted that when pin 3 is at turning point 25, the pin is under extra tension (the combined thickness of railing, body and skirt being greatest at this point) so that the cover will snap shut when this extra tension is relieved in closing the cover. Similarly the cover will snap open in the reverse operation.

Padding 20 having groove 21 is held in place by cardboard reinforcing 24. Because the padding is inserted into the body before the skirt is attached, a considerable saving in time and expense is effected. Firstly, the reinforcement for the padding is less complicated; secondly, it is easily inserted in the body; thirdly, it is not glued or cemented in position; and fourthly, no extra care need be taken to hide the raw edges of the padding. These advantages are obtained because the opening in the body is larger before the skirt is attached and also because the skirt hides the raw edges and holds the padding in place.

Figure 3 is a back view of the box with cover 1 in a raised position, and illustrates pin 3 in position in slot 14. Other members shown in this figure have been described heretofore, the same numerals being assigned to the same parts, as has also been done in the description of all of the figures.

I claim as my invention:

1. A box comprising, in combination, a body having sides, a front and a back, a top opening, a slotted opening in said back and raised railings on the inside of said back extending parallel to said slotted opening, a cover having a raised member on the inside thereof inserted in said slotted opening, a pin attached to said raised member and extending across said railings, the clearance between the pin and the inside of said cover being less than the thickness of said body and railing, whereby the ends of the pin are bent and the pin is under tension, and an inside cover comprising a flat frame member attached to said body and framing said top opening.

2. A box comprising, in combination, a body having sides, a front and a back, a top opening, a slotted opening in said back and raised railings on the inside of said back extending parallel to said slotted opening, a cover having a raised member on the inside thereof inserted in said slotted opening, a pin attached to said raised member and riding along said railings, whereby

said cover may be raised and lowered along the back of said body, the clearance between said pin and the inside of said cover being less than the thickness of said body and railing, whereby the ends of the pin are bent outwardly and the pin is under tension, thereby holding said cover in any position at the back of said body, and a skirt comprising a flat frame top member and an outwardly extending lower section adapted to fit on said body, said skirt comprising both an inside cover for said body by framing said top opening and a front for said box.

3. In a box construction, a body having sides, a front and a back, a top opening, a slotted opening in said back, raised railings on the inside of 15

said back extending parallel to said slotted opening, a cover having a raised member inserted in said slotted opening, a pin attached to said raised member of said cover and extending across said raised railings on the inside of said back.

LEONARD SOFO.
